CLAIM

I claim the ornamental design for the jeweled watch and band, as shown and described.

DESCRIPTION

The links of the jeweled band of the jeweled watch and band have clear transparent windows on the top side (see FIG. 1) and the bottom side (see FIG. 2) which together with the link frame form a chamber. Free-floating jeweled stones (three) are in each chamber. The free-floating jeweled stones move within the chambers as the jeweled watch and band are moved.

FIG. 1 is a top view of the jeweled watch and band of the present invention;

FIG. 2 is a bottom view of the jeweled watch and band of FIG. 1;

FIG. 3 is an end view from the top end of the jeweled watch and band of FIG. 1;

FIG. 4 is an end view from the bottom end of the jeweled watch and band of FIG. 1;

FIG. 5 is a side view from the right side of the jeweled watch and band of FIG. 1; and,

FIG. 6 is a side view from the left side of the jeweled watch and band of FIG. 1.
